(57) **CLAIM**

The ornamental design for a communication service trailer, as shown and described.

DESCRIPTION

FIG. 1 is a front perspective view of the communication service trailer showing my new design as seen from the front right;

FIG. 2 is a rear perspective view thereof as seen from the left rear;

FIG. 3 is a right side elevational view thereof;

FIG. 4 is a left side elevational view thereof;

FIG. 5 is a front elevational view thereof;

FIG. 6 is a rear elevational view thereof; and,

FIG. 7 is a top plan view thereof.

The bottom of the trailer is substantially unornamented.
